United States Patent Office

Des. 207,075
Patented Feb. 28, 1967

207,075

HOLDER FOR DRAFTSMAN'S TOOLS AND THE LIKE

Jacque Fresco, 3112 W. 23rd St., Miami, Fla. 33140

Filed June 1, 1966, Ser. No. 2,505

Term of patent 14 years

(Cl. D74—5)

FIG. 1

FIG. 2

FIG. 3

FIG. 4

FIG. 5

FIG. 6

FIG. 1 is a front elevation of a holder for draftsman's tools and the like, showing my new design.

FIG. 2 is a rear elevation thereof.

FIG. 3 is a top plan view thereof.

FIG. 4 is a bottom plan view thereof.

FIG. 5 is an end elevation thereof.

FIG. 6 is a cross sectional view taken through section line 6—6, FIG. 1.

FIG. 7 is a perspective view thereof.

I claim:

The ornamental design for a holder for draftsman's tools and the like, as shown.
